Patented Feb. 8, 1966

203,679

REPERTORY DIALER TELEPHONE SET

James N. Burlin, New York, N.Y., and Stanley E. Seretny,
Indianapolis, Ind., assignors to Bell Telephone Laboratories,
Incorporated, New York, N.Y., a corporation of
New York

Filed Mar. 19, 1965, Ser. No. 84,364

Term of patent 14 years

(Cl. D26—14)

FIG. 1

FIG. 1 is a front perspective view of a repertory dialer telephone set showing our new design; and

FIG. 2 is a side view thereof.

The dominant features of our new design are shown in solid lines in the drawing.

We claim:

The ornamental design for a repertory dialer telephone set, as shown and described.
